SAFETY RAZOR

William C. Pattiani, Oakland, Calif.

Application January 9, 1951, Serial No. 205,118

6 Claims. (Cl. 30—60.5)

1

This invention relates to a safety razor of the type employing a sectional cap in combination with a guard or other blade-supporting member.

It is in general the broad object of the present invention to improve the accuracy and speed of the blade-clamping and releasing operation, and to facilitate convenient manipulation of the razor by the user.

In using safety razors of this general type, it has been usual heretofore to effect the blade clamping operation by manipulation of a handle member threaded or provided with a spiral or inclined cam surface, designed to impart a clamping movement to the sectional cap when the handle member is turned by the user. As distinguished from such prior construction, the present invention contemplates cap sections which are arranged to be moved into clamping position initially by a simple downward pull upon the handle or manipulating member, the latter being thereafter turned less than a quarter turn to secure the blades in position and under the desired tension. When it is desired to open the razor, a twist of the handle releases the lock provided upon the cap sections, which are then moved into open position under the bias of a spring.

Certain important advantages are inherent in a structure of this character. For example, the closing movement of the razor can be effected very quickly and under very sensitive control. Further, the razor is readily opened and one familiar with the razor can achieve this with one hand, leaving the other hand free to remove the used blade and insert another. It is therefore an important feature of the invention to provide a safety razor having sectional cap members in combination with a spring, tending at all times to move the cap members into open position in combination with mechanism under the control of the user for opening and closing the cap sections with a minimum of movement and for controlling the action of the spring. In the razor shown as embodying the present invention, the razor is so organized that a single spring controls the pivotal movement of the cap sections to open position, as well as their joint movement toward closed position for clamping the blade and imparting a transverse curvature to the blade.

Another feature of the razor of the present invention consists in providing spring actuated sectional caps so organized and arranged that, in addition to the cap opening movement, the

2

spring also serves the purpose of holding the cap sections yieldingly in open position and providing a desired tension upon the cap section closing means.

5 The invention includes other objects and features of advantage, some of which, together with the foregoing, will appear hereinafter, wherein the present preferred form of razor embodying the invention is disclosed. In the drawings accompanying and forming a part hereof:

Figure 1 is a side elevation of the preferred form of razor chosen to depict the present invention.

15 Figure 2 is a longitudinal section taken through the razor shown in Figure 1.

Figure 3 is a side elevation, partly in section, with the razor shown with the cap sections in open position for removal or insertion of another blade.

20 Figure 4 is a plan view of a spring utilized in the razor.

Figure 5 is a perspective view of the guard and handle portion of the razor.

25 Figure 6 is a fragmentary side elevation, partly in section, of the razor in closed position with the blade omitted for convenience.

Figure 7 is a view showing the cam surfaces as developed along a plane.

In the preferred embodiment of the present invention the guard 10 is utilized as a blade-supporting member for shaping the blade when it is clamped in shaving position. The guard 10 is readily constructed of heavy sheet metal and is provided along its longitudinal edges with a guard rail 11 of the usual construction. It can be formed by die-pressing and bending a single blank and is provided with an elongated depressed recess or chamber 12 of diamond-shaped contour and this chamber is bounded about its upper margin by outwardly extending convex blade supporting faces. The guard is provided centrally at each end with a slotted opening 45 through the wall of the chamber 12 to permit the passage of the opposite terminal ends 21 of the bar 19 to be presently described. It is also provided adjacent each corner with a rectangular opening or notch 13 to permit the free passage of the cap section arms 25.

50 The guard 10 is rigidly connected to a tubular head 14, as is shown in Figure 2, the inner end of the head 14 being spun or riveted to fill a counter-sunk opening in the bottom of the recess 12. The head is shouldered near its lower end to receive the handle barrel 15. Within the barrel is disposed a spindle 18 threaded at its

lower end into a cylindrical plunger 28 which is mounted within a cap 20 rotatably mounted upon and closing the lower end of the handle barrel 15.

In the upper end of the spindle 18 is mounted the downwardly extending stem of the cross bar 19. The bar is made by longitudinally folding a sheet metal blank and its opposite ends 21 are offset downwardly and pass out through the slots in the ends of the recess 12 of the guard (see Figure 4 in Patent 2,043,124 for a detailed showing of a suitable bar). The offset ends of bar 19 terminate in outwardly extending transverse arms 22 which extend across the ends of the guard and are movable freely up and down with the bar 19 and its spindle 18 and independently of the guard.

In Figure 3 is shown a typical form of blade 23 suitable for use in the razor of my invention. It is of well-known form and is provided with a central longitudinally extending blade-locating slot designed to fit accurately upon the bar 19 and has reentrant recesses in each corner which define an elongated unsharpened centrally disposed portion at each end of the longitudinal edges for shaving and the slot may be provided with spaced transverse enlargement for the reception of blade-locating studs of various shapes in other safety razors; one can refer to Figure 4 in the aforementioned patent for a showing of such a blade.

The transverse arms 22 of the bar 19 are located beneath the elongated ends of the blade 23 and act to lift the blade and move it above the blade-engaging face of the guard when the bar 19 and the carrier structure associated therewith is moved upwardly.

The cap sections 24 are transversely concave in contour and cooperate with the guard 10 in imparting a transverse curvature to the blade when the latter is clamped in shaving position. Each cap section 24 is provided at each of its outer corners with a downwardly extending bell crank 25 having arms 20 and 26, each bell crank being pivoted as at 46 to the outwardly extending arms 22 of the carrier bar 19. Arm 20 of each bell crank 25 is connected to a cap section 24 and is adapted to pass downwardly through one of the recesses 13 in the corners of the guard. Each bell crank includes intermediate its ends a semi-circular cam 30 which cooperates with the stationary shoulder of the guard adjacent the recess 13 when the carrier is raised to swing the cap sections into open position as the carrier is moved upwardly. In this movement the arms 20 swing outwardly into substantially horizontal position, as shown in Figure 3 and the cap sections rest upon the guards 11, the arms 26 extending almost vertically in this position of the cap sections. In the downward movement of the carrier bar 19, the pivots 46 of the arms 25 being moved past the walls of the recesses 13, the arms 20 are swung upwardly and the cap sections moved toward their closed position, the arms 26 turning and passing endwise through the notches 13.

Spindle 18 and associated parts are normally urged upwardly by a flat leaf spring 29 (Figure 4) having an aperture 30 therein through which the stem of the bar 19 passes; this spring is shown in Figure 4 and includes opposite fingers 31 which ride against the underside of bar 19. The spring includes a base 32 from which fingers 31 extend, the base being generally of such con-

figuration that it fits snugly in the diamond-shape recess or chamber 12.

The end of handle barrel 15 is provided with two like cams 36, these being separated by slots 37 on each side of the handle barrel. A pin 38 is extended through the cap 20 after plunger is threaded in the spindle 18. Spring 29 serves as an actuating member to move the spindle 18 and carrier 19 upwardly when permitted so to do.

When the razor is to be opened to permit the removal of the blade for purpose of cleaning or replacement, the user turns the cap 20 as between the thumb and forefinger to release the locking engagement of the pin and the cams. As soon as the pin has passed into the slots 37, the cap sections 24, bar 19 and other associated parts are moved into open position under the bias provided by the spring, the parts being retained in this position.

When it is desired to close the razor and condition it for use, a blade being in place, it is only necessary to slide the cap member 20 downwardly with respect to the handle barrel 15 until the pin has passed out of the slot sufficiently to permit it to ride along a first cam portion 36 which is provided on each side of the slot 37. Each first cam portion extends radially of the handle and downwardly away from the guard so that as the pin rides over the first cam portions, the spindle 18 is drawn down in the handle 15 and the caps are moved into blade covering position while spring 29 is tensioned. Thus, as the pin moves over the first cam portion 36, the tension on the caps is increased so that the desired curvature can be imparted to the blade and the cap sections locked. It is to be noted that a second cam portion 40 extends upwardly and away from each first cam portion 36. If the pin is moved over peak 52, which provides a junction between the two cam portions, the guard and blade will be locked positively in position, the pin then being in a position nearly 180° from its original position.

From the foregoing, I believe it will be apparent that I have provided a novel, simple and improved form of safety razor construction.

I claim:

1. A safety razor comprising a guard having a tubular handle secured thereto, a carrier having a pair of cap sections pivotally mounted thereon and a stem extending into said handle, a spring mounted between the guard and the carrier and tending at all times to move the cap sections into open position with respect to the guard, a cap threadedly engaged with said stem and rotatably mounted on an end of said handle, a slot in the end of said tubular handle dividing the said end into two separate cams, each including a first and a second cam portion, the first cam portion extending circumferentially of said handle and axially of said handle away from said guard, the second cam portion extending circumferentially of said handle and continuing the first cam axially toward said guard from that portion of the first cam furthest from said guard, a pin extending from said cap into said slot movable upon emergence from said slot first over said first cam and then over the second cam to lock the cap sections in a desired position.

2. A safety razor comprising a guard having a tubular handle secured thereto, a carrier having a pair of cap sections pivotally mounted thereon and a stem extending into said tubular handle and slidable therein, a spring mounted between the guard and the carrier and tending at all times to move the cap section into open posi-

tion with respect to the guard, a cap member rotatably mounted on the end of said tubular handle and threadedly engaged with said stem, a slot in the end of said tubular handle, a cam surface on the end of said tubular handle extending axially and circumferentially away from said slot, and a pin mounted in said cap member for initial longitudinal sliding movement with said stem to close said cap members followed by simultaneous rotary movement and an axial movement along said handle away from said guard along said cam surface for locking the cap members in a selected position.

3. A safety razor comprising a blade supporting member having a recess therein and a tubular handle secured thereto at one end thereof, a carrier having a bar extending across said member and spaced therefrom, a pair of cap sections pivotally mounted on the bar, a stem extending from said bar slidably into said handle, a single flat leaf spring fitting said recess and having opposite ends thereon engaging the under side of the bar to bias the carrier to swing the cap sections into open position, and means for moving the stem axially of said handle to swing the cap sections to closed position.

4. A safety razor comprising a blade supporting member having a recess therein and a tubular handle secured thereto at one end thereof, a carrier having a bar extending across said member and spaced therefrom, a pair of cap sections pivotally mounted on the bar, a stem extending from said bar slidably into said handle, a flat leaf spring fitting said recess and having opposite ends thereon engaging the under side of the bar to bias the carrier to swing the cap sections into open position, a cap threadedly engaged with said stem and rotatably mounted on the other end of said handle, a cam formed on said other end of said handle and having a face thereon extending circumferentially of said handle and axially of said handle away from said carrier, a slot extending longitudinally of said handle and defining terminal ends of said cam, and a pin extending from said cap to move in said slot and movable over said cam to open and lock close said cap sections.

5. A safety razor comprising a guard having a tubular handle secured thereto, a carrier having a pair of cap sections pivotally mounted thereon

and a stem extending into said handle, a flat leaf spring mounted between the guard and the carrier and tending at all times to move the cap sections into open position with respect to the guard, a cap threadedly engaged with said stem and rotatably mounted on an end of said handle, a slot in the end of said tubular handle, a first and a second cam cooperatively adjacent said slot, the first cam extending circumferentially of said handle and axially of said handle away from said guard, the second cam extending circumferentially of said handle and continuing the first cam axially toward said guard from that portion of the first cam furthest from said guard, a pin extending from said cap into said slot movable upon emergency from said slot first over said first cam and then over the second cam to lock the cap sections in a desired position.

6. A safety razor comprising a blade supporting member having a recess therein and a tubular handle secured thereto at one end thereof, a carrier having a bar extending across said member and spaced therefrom, a pair of cap sections pivotally mounted on the bar, a stem extending from said bar slidably into said handle, a flat leaf spring fitting said recess in the blade supporting member and having opposite ends thereon engaging the underside of the bar to bias the carrier to swing the cap sections into open position, a cap threadedly engaged with said stem and rotatably mounted on the other end of said handle, a cam formed on said other end of said handle and having a face thereon extending circumferentially of said handle and axially of said handle away from said carrier, a slot extending longitudinally of said handle and defining the terminal ends of said cam, and a pin extending from said cap to move in said slot and movable over said cam to open and lock close said cap sections.
